UNITED STATES PATENT OFFICE.

ARTHUR H. EDDY, OF WINDSOR, CONNECTICUT.

CARBURETOR.

REISSUED

Application filed October 23, 1917, Serial No. 198,144. Renewed October 26, 1922. Serial No. 597,138.

To all whom it may concern:

Be it known that I, ARTHUR H. EDDY, a citizen of the United States, residing at Windsor, in the county of Hartford and 5 State of Connecticut, have invented new and useful Improvements in Carburetors, of which the following is a specification.

This invention relates to the art of vaporizing liquids in general, and particularly to 10 the vaporizing of liquid fuel and hydrocarbon liquids of relatively high boiling points, and to the production of a fixed gas from such vapors.

The principal object of the invention is 15 the efficient vaporization of liquid fuel and hydrocarbon liquids of relatively high boiling points, and as the invention finds, so far as now known, its greatest field of usefulness in that application, I will describe the vaporization as carried out in connection with, and the apparatus embodying the means for 20 operation with, such materials, it being understood that both the principle involved and the apparatus may be useful with other 25 liquids.

The invention includes, in its physical embodiments, constructions in apparatus for transforming liquids into vapors and then heating and cracking said vapors to produce 30 a fixed gas, and also to the formation of explosive mixtures by combining the vapor or gas with air.

In the vaporization of liquid fuel and hydrocarbon liquids of relatively high boiling 35 points, such as distillates, including kerosene and fuel oils, it has been found that when the vapor is produced with apparatus now in use in conjunction with a small amount of heat, the vapor is coarse and 40 unsuitable for use at high efficiency for the reason that all of the vapor is not consumed at the temperature and in the time of subjection to the combustion temperature. This is particularly true when the combustion 45 takes place in internal combustion motors. It has been found, also, that vaporization of such fuels or oils by the employment of a wick to burn a small portion of the oil with restricted air supply to heat the balance of the oil, is objectionable for the reason that the wick cakes up and a large 50 amount of smoke is produced which results in the deposit of quantities of carbon. Further, the hot tube vaporizer, in which oil 55 is sprayed under pressure into a heated tube,

has been found unsatisfactory for the reason that the tube chokes up with carbon and must be frequently cleaned out or replaced.

My invention involves reducing the oil by mechanical means to an exceedingly fine 60 state of subdivision, that is, vaporizing it, and then utilizing this vapor in any suitable manner. This I accomplish by subjecting the oil to combined pressure against and friction with a surface so that the adhesion 65 of the liquid to the surface is greater than the cohesion of the liquid. The result is that the liquid is vaporized to an exceedingly high degree of fineness and when visible appears like a greyish white smoke. This action with the surface I obtain by centrifugal force, the surface being inclined at an angle to its axis of revolution and the oil supplied to the surface so as to be caused to flow along and against the same. This surface is 70 preferably in the form of a cone rotated at very high speed, the angle of inclination of the surface with the axis and the speed of rotation being selected according to the density of the liquid treated. One effective 75

angle of inclination is shown in the drawings, and the area of surface and size of cone are also factors to be considered in connection with speed and output. The speed may be six thousand revolutions, and may even 80 reach thirty thousand revolutions per minute. Under such conditions the pressure of the liquid against the cone surface is so high, and the friction so great that the liquid is vaporized while it passes along the 85 surface and before it reaches the edge thereof. While I do not fully understand the theory of the action which takes place I believe that the excessive pressure against the surface causes a heating friction between 90 the liquid and surface, and possibly between the particles of liquid also, so that the oil is entirely vaporized and rises from the surface in the form of a fine mist or fog and the liquid is torn apart and a high degree of 95 fineness of vaporization results. My experiments show that the liquid does not reach the edge of the cone, but leaves the cone surface fully vaporized before reaching the edge. If allowed to reach the edge of the 100 cone, it would be thrown off in coarse spray not suitable for efficient use.

In order to secure the necessary high speed of rotation of the cone, I employ a direct connected electric motor designed for 110

sufficient speed. The power consumed, the watts used in running the motor, seems to indicate that the above theory is correct, as corresponds substantially to the heat units 5 which would be required for vaporization. The work done in the actual vaporization may be ascertained by subtracting the amount done in rotating the cone without the liquid from that done rotating the cone 10 with the liquid. Actual measurements show that the former is only about one-fourth of the latter.

I am aware that it has been proposed to employ various forms of surfaces, including 15 the conical form rotated at low speed as by the suction of an internal combustion motor. In these devices the liquid is thrown off from the edge of the surfaces as coarse spray. Others have proposed to rotate various 20 disk constructions by power, but in such construction the action of the liquid on the disk has not resulted in the complete vaporization which makes the vapor or fog rise from the surface of the disk before reaching 25 the periphery of the disk.

In the practice of the invention the oil is supplied to the cone surface in such quantity as to form a thin layer or film, and the rate of flow of the supply may be regulated 30 according to the conditions.

The vapor produced as above indicated may be utilized in any suitable manner, as by supplying it to a burner or mixing it with air and burning it in an internal 35 combustion motor. In these uses the vapor is highly efficient, especially in warm weather, but as a further improvement I prefer to convert it into a fixed gas. This may be accomplished, owing to the 40 fineness of the vapor, by bringing it in contact with a heated surface or heated surfaces of the proper temperature to crack the oil and convert the vapor into a permanent gas. The gas so produced gives remarkably 45 efficient results as compared with the vapor.

The present invention relates to carburetors in general and particularly to carburetors for producing combustible mixtures of fuel and air for use in internal combustion 50 engines or other power plants, and provides a carburetor for producing a gas in one chamber and mixing it with air in another chamber, and adapted to operate without regard to the operations of the internal combustion engine to which it may be fastened.

One object of the invention is to provide an apparatus for producing unusually efficient combustible mixtures of liquid hydrocarbon material and air in accordance with 55 the hereinbefore described explanation.

A further object of the invention is to provide an apparatus for using hydrocarbon oils of relatively high specific gravity and which are slow to vaporize and which hereinbefore have not been used advantageously in

explosive mixtures for internal combustion engines.

A further feature of the invention includes the particular design of the parts of the structure, the relative location and the operative relation of the parts by which the efficiency of the apparatus and the process is obtained.

A further object of the invention includes the apparatus whereby hydrocarbon 75 oils having high boiling points are transformed into a vapor state and the heat treatment of such material while in a vapor state to so change its nature that it may be used to advantage to form hydrocarbon oils having 80 low boiling points, and mixed with air to afford highly efficient explosive mixtures as hereinbefore described.

The invention provides a rotatable conically shaped vaporizer, a high speed electric motor directly connected to said vaporizer, and means for applying liquid fuel to the same, the centrifugal action of the vaporizer causing the fluid to be delivered as a fog or vapor and not in the form of a sheet of fluid.

Further features of the invention pertain to valves and specific control means for operating the same and the other adjustable parts of the carburetor.

The above features and others to be specified are described and claimed in the following specification and claims and illustrated in the accompanying drawings, in which—

Figure 1 represents a central vertical section through the carburetor showing the float in the base of the structure, the centrifugal vaporizer cone, the electric motor directly connected to the same, and the valves which are shown in the closed position.

Figure 2 is a sectional view similar to Fig. 1 but showing the lower or primary air valve partly open.

Figure 3 is a sectional view similar to Figs. 1 and 2 but showing the primary air valve wide open and the secondary or upper air valve slightly open.

Figure 4 is a top plan view of the carburetor looking down on the electric motor and the regulating apparatus.

Figure 5 is a view of the regulating cams looking upward.

Figure 6 is a top plan view of a casing 120 with the motor and regulating cams removed showing the top of the plunger rods which are connected to the valves within the casing.

Figure 7 is a sectional view showing a 125 modification having an annular heating chamber immediately surrounding a vaporizing chamber and showing tangential gas jets or nozzles for furnishing a gas flame for heating the wall of the vaporizing cham- 130

ber. In this arrangement the vaporized and cracked material is drawn off of the vaporizing chamber and passed through suitable separators or condensers.

5 Figure 8 shows the arrangement of the gas jet nozzles and the valves for regulating the same which may be used with the structure shown in Fig. 7.

In the drawings like numerals indicate 10 like parts throughout the various figures.

1 is the main casing of the carburetor formed to provide an air inlet passage 2 which may open directly to the atmosphere or receive hot air from any suitable heating 15 source. At the bottom of the casing 1 is the fuel inlet passage 3 which communicates with a float chamber 4 located centrally in the lower part of casing 1. A float 5 having a central opening is mounted within 20 said chamber 4 to operate a valve 6 controlling the passage of fuel past the valve seat 7. The rising movement of the float 5 will raise the outer ends of the levers 8 to which it is connected and thereby lower 25 the valve 6 which is mounted on the valve guide rod 9 in engagement with the inner ends of the levers 8. It will be observed that the lower end of the guide rod 9 is loosely held within the valve inlet passage 3 30 and that the upper end is loosely held in an upper support member 10 and that ample space remains along the rod 9 for the passage of fuel.

In the upper part of the casing located 35 centrally and immediately above the float chamber 4 is a circular vaporizing chamber 11 having oblique walls 12 flaring outwardly and upwardly from the side walls of the float chamber 4. The roof of the vaporizing 40 chamber 11 is formed by the upper surface of the main casing 1 and is substantially imperforate to the passage of air. The air inlet passage 2 is divided and provides an annular passage immediately surrounding the vaporizing chamber 11 and concentric with 45 the walls thereof. Immediately surrounding the walls of the float chamber 4 and separated from the air inlet passage 2 by a wall 13 is an annular chamber 14 in which the vaporized fuel and air are mixed as will be 50 further described. A discharge outlet 15 communicates with the mixing chamber 14 and is provided with a throttle valve 16.

This discharge outlet 15 is designed to be 55 directly connected with the intake manifold of any suitable internal combustion engine or similar power unit. A plurality of passages or ports 17 are provided through the oblique wall 12 of the vaporizing chamber 60 and connect this chamber with an intermediate heating chamber 18 which is concentric with the float chamber 4 and the vaporizing chamber 11 and which is substantially below the oblique walls 12 of the vaporizing 65 chamber. Additional discharge passages or

ports 19 are provided through the side walls of the chamber 18 communicating with the mixing chamber 14. A covering of wire gauze 20 surrounds the outer wall of the chamber 18 and covers the ports 19 to prevent the passage of any flame should a back fire occur into the outlet passage 15 from the engine on which the carburetor is being used.

The wall 13, at a height directly opposite the ports 19 and gauze 20, is provided with 70 an annular opening 21 extending around the same. A circular valve member 22 is slidably mounted on the cylindrical outer surface of the wall 13 and above the opening 21 and has a flange extension adapted to seat 75 on the upper surface 13^a of the lower side of the wall 13.

A high speed electric motor 23 is mounted on its vertical axis above the casing 1 and has a downwardly projecting rotatable hollow drive shaft 24 which projects into the casing 1 and downwardly to a point just below the surface of the liquid fuel in the float chamber 4. A conical vaporizer 25 is mounted on the shaft at the lower end thereof. 90 This vaporizer cone has a circular periphery and is provided with straight oblique imperforate walls extending from the point of fastening on the shaft 24 to the immediate periphery which is slightly bent to form a narrow horizontal rim as indicated at 25^a. The mounting of the cone 25 on the shaft 24 is accomplished by means of a concial member 26 carried by the shaft 24 and pointing downward. The vaporizer 25 is adapted to 95 fit over this concial member 26 and has an enlarged opening to receive the shaft 24 and a flange 27 projecting vertically downward.

A complementary clamping member 28 having a central bore 28^a is screwed upon the lower end of the shaft 24 and clamps the cone 25 firmly against the cone 26, the flange 27 assisting in centering the cone. The lower end of the cone 26 is adapted to project into the central opening of the float 5 and into 110 the liquid fuel in the float chamber 4. Passage for the fuel to the upper surface of the cone 25 is provided by the central bore 28^a, the passages 28^b which extend from the bore 28^a to the cone 26, and the channels 26^a formed in the surface of the cone 26 and providing means for conducting the liquid 115 between the cone 26 and the vaporizer cone 25 to the upper surface of the latter. The plurality of channels assists in directing the liquid fuel in even amounts to the cone 25. Control means for the bore 28^a is provided by a tapered valve member 29 which seats against the side walls of the bore 28^a and is carried by a valve rod 30 which extends upwardly through the hollow shaft 24 to a point near the top of the vaporizing chamber at which point a sliding collar 31 is mounted on the shaft 24. A pivoted lever 32 having a yoke 33 is mounted to engage the 120 125 130

collar 31 to operate the valve and external control means is provided for actuating the lever 32 as will be described.

Heating means for treating the vaporized fuel discharged from the periphery of the cone 25 is provided by a circular metal wire or band 34 mounted within the vaporizing chamber and spaced from the periphery of the cone and on a level therewith. This band 10 is electrically heated and is suitably insulated from the walls 12 of the vaporizing chamber. A source of electricity for heating the member 34 is shown at 35 and suitable rheostat control means is indicated at 36. 15 Connections from the electrical source to the band 34 are insulated through the casing 1. Additional heating means 37 is provided for the chamber 18 and similar connections are made with the source of electricity as for the 20 band 34.

A secondary air valve is provided between the air intake passage 2 and the vaporizing chamber 11 as indicated by the slidable ring 38 which is circular and slidably mounted on 25 the cylindrical flange 39 and which is adapted to seat against the rim 40 at the upper edge of the side walls 12 of the vaporizing chamber. The opening made by movement of this secondary air valve 38 will extend 30 around the entire vaporizing chamber and will be at a height directly opposite the band 34 and on the opposite side of the same from the edge of the cone 25.

The control means for operating the carburetor comprises a spider member 41 which is mounted on the shaft 24 above the casing 1 and between the casing 1 and the motor 23. This spider member has three radial arms which are divided at their outer ends to 40 provide support means for a double annular ring 42 slidably mounted in said divided ends. At the outer end of said radial arms and on the under surface of each there are two cams 43 and 44. Circumferential movement of the spider member arms causes the cams 43 and 44 to engage the upper ends of the plunger members 43^a and 44^a which are connected directly to the primary air valve 22 and the secondary air valve 38 respectively. When not engaged by the cams 43 and 44 the plunger members 43^a and 44^a will be raised by the springs 43^b and 44^b which are normally under compression. Therefore it will be clear that when the air 55 valves are closed the cams 43 and 44 are in engagement with the respective plungers and that the latter are held down by the cams. Looking down on the carburetor, a clockwise movement of the spider arms will 60 actuate the cams to allow the plungers to rise and the air valves to open. Mounted on the ring 42 is a secondary cam member 45 which is adapted to engage the end of the cam 43 to alter the pitch or inclination 65 of the cam surface. This adjustment is

made by means of sliding the ring 42 circumferentially with respect to the spider arms and the cams 42. This adjustment is made by means of a set screw 46 mounted on the upper surface of the ring 42 and connected to the upper side of the forked end of the spider arm. By this arrangement the opening of the valve 22 and the valve 38 is so timed that either valve may be opened in advance of the other according 70 to the way in which the cams have been set. However it is seldom necessary or desirable to open the secondary air valve 38 and therefore it is usually desirable to allow the free play of the push rod 43^a before the push rod 44^a is allowed to be relieved and moved upward. 75

Mounted on one of the spider arms and between the split end of the same and the center bearing there is a cam member 47 on 80 the under surface of the spider arm for actuating a plunger rod 48 which is directly connected to the lever 32 within the vaporizing chamber. The operation of this plunger is similar to the plungers for operating 90 the air valves and suitable set screws are provided above the spider arm for adjusting the pitch of the cam 47 which will directly affect the rate of flow of the fuel through the lower end of the conical vaporizer 95 25.

The control means includes a connection 49 between the spider 41 and the throttle valve 16 so that movement of the throttle valve will turn the spider member accordingly. An opening movement of the throttle valve will move the spider 41 in a clockwise direction and relieve the plungers to open the primary air valve and the fuel valve. At the same time a connection 50 from the connection 49 operates to rotate 100 the vaporizer cone by applying power to the electric motor. A connection 51 also connected to the part 49 automatically operates the rheostat to heat the elements 34 and 37. 105

In the top of the casing 1 is a nozzle or opening 52 for connecting a small pipe or tube for the injection of steam or water from a suitable source. It may be desirable to apply a wrapping of tubing about the exhaust manifold of the engine so that steam or water may be furnished at the proper temperature to the vaporizing chamber. 115

The operation of the carburetor provides for the inflow of liquid fuel into the base 120 of the casing and up into the float chamber 4 to a point above the lower end of the conical clamping member 28. A constant flow of fuel is provided for through the valve member 29 by means of a minute opening extending from the end of the valve and connecting with the inside of the bore 28^a above the valve seat. However in the operation of the motor and a heavy demand 125 on the carburetor, after the valve 29 is de- 130

pressed by actuations of the plunger 48, the fluid will rise within the passages 28^b and will be forced centrifugally through the channels 26^a onto the upper surface of the 5 rapidly rotating cone 25. The oil moves in a thin film upward over the surface of the cone and is discharged from the same in the form of a fog and in a vapor state. There is no sheet of fluid discharged from 10 the edge of the cone. This result is obtained by the particular construction of the vaporizer cone and its mounting together with the fact that the electric motor is designed to operate at very high speeds. It is not necessary 15 that the motor be restricted to an electric motor but it is necessary that tremendous speeds be furnished. In one form of apparatus which has been successfully used with a light oil a speed of 6000 R. P. M. 20 was used. Speed requirements must also vary with the viscosity of the material treated and temperature. A small turbine motor having a powerful blast for driving the same might accomplish the same results 25 if sufficient speed could be obtained. The movement of the liquid on the inner surface of the cone has been described as follows. Centrifugal force impels the liquid outwardly against the surface of the cone to which 30 it adheres. Additional particles of liquid, on being supplied to the cone, flow over those adhering to the surface and in turn adhere thereto. Under correct conditions the liquid thus spread out is vaporized before it reaches 35 the outer edge of the cone. The reason for this action, as at present understood, may be summarized in the statement that the heat generated as result of the adhesion of the liquid to the cone surface being greater 40 than the cohesion of the liquid, is sufficient to vaporize the liquid. In other words, when a given amount of liquid is spread sufficiently, the heat that is in the energy used to force the liquid out over the surface is 45 sufficient to vaporize it. The conditions necessary for proper vaporization vary with the nature of the liquid and the speed, lighter oils vaporizing at lower speeds and with less power than the heavier oils. It is 50 understood that the centrifugal force impels the particles of liquid against the surface of the cone with a force several thousands times greater than the cohesion of the particles of the liquid. To rotate the vaporizer 55 idly, that is without the application of liquid to the surface it has been found that but four units of work have been required as compared to the twenty units required when liquid is being fed to the cone surface. It is 60 estimated that this difference is consumed in overcoming and breaking up the liquid, and that this work, perhaps in the form of heat is taken up by the liquid and by the cone. Or it may be that the film is torn 65 apart and thus broken up into minute par-

ticles which constitute the very fine mist or fog referred to. When the fuel is discharged from the cone, it rises from the surface of the cone in the form of a fine mist or fog and moves as a cloud of vapor directly 70 against and over the electrically heated member 34 and while it is in a vapor state the material is cracked so that it is possible to use in this apparatus oil which has heretofore been too heavy to be successfully 75 used for forming combustible mixtures. In the performance of the carburetor complete vaporization of kerosene and other oils in the form of a very fine mist or fog rising from the inner surface of the cone is 80 effected without the use of heat, and the vapor so produced may be mixed with air as above specified. In addition, it has been found that such vaporization is accelerated 85 and facilitated by the heating action of the heating coil and this form of heat may be employed to raise the temperature of the high speed revolving cone and thereby the kerosene or other oil being acted upon. My invention therefore contemplates the em- 90 ployment of a certain amount of heat to assist in the vaporizing action when desired, as well as in the vaporization effected solely by the action of the high speed revolving cone upon the fuel alone. 95

In using the term fine mist or fog, I contemplate the very fine mist or vapor produced by my process and apparatus, as distinguished from a coarse vapor or spray, for instance, this very fine mist or fog con- 100 stitutes a nebula, which, when permitted to rise in the air from the surface of the revolving cone, remains suspended and floats off in the air for a considerable length of time. 105

While I have discussed the application of my invention to kerosene and other hydrocarbons which are heavier than the very light hydrocarbon commonly known as gasoline, I wish it understood that my apparatus 110 may be used, and has been used by me, with gasoline, in which case highly satisfactory and desirable results were produced.

When the control means is actuated the vaporized fuel is discharged from the cone, 115 is heat treated by the member 24, and passes out through the port 17 and 19 into the mixing chamber 14 meeting the inflowing air which passes through the valve 21 after the valve 22 is raised. The air and vaporized 120 fuel is mixed at this point and passes out of the mixing chamber 14 into the discharge passage 15 controlled by the throttle valve 16. Should it be desirable to raise the valve 125 38, this may be done by relieving the pressure on the upper end of the plunger 44^a and allowing the opening at 40 to permit the entry of a minute amount of air directly against the opposite side of the heating member 34. In this instance the mixed air 130

- and fuel would be sucked out through the mixing chamber as fuel, the amount of air probably being insufficient to form a combustible or explosive mixture until it meets
- 5 the main flow of air through the valve 21. In order to prevent the liquid within the float chamber from climbing up on the outer surface of the cone an annular flange is provided on the member 28 as indicated at 28^b.
- 10 Any material that travels up the outside of the member 28 will be discharged centrifugally from the edge of this flange and will not be thrown against the lower surface of the cone 25 and during the rotation of the
- 15 vaporizer cone cannot travel past the flange 28^b.

Referring in detail to Figs. 2 and 3 it will be observed that in Fig. 2 the valve 22 is allowed to rise slightly and that the valve 20 38 has not been moved. In this view the valve for fuel has been moved by the downward movement of the plunger 48 depressing the lever 32. Referring to Fig. 3 it will be noted that the valve 22 is wide open and 25 that the valve 38 has been slightly raised and that the lever 32 operating the fuel valve has been lowered still further than shown in Fig. 2.

Referring in detail to the views shown in 30 Figs. 7 and 8 it may be noted that the structure shown in these views is a modification for heating the fuel or hydrocarbon material as it is discharged from the vaporizer cone. This structure is particularly adapted 35 for use in the cracking of heavy hydrocarbon oils and the preparation of volatile products and the production of hydrocarbon oils having low boiling points. The apparatus shown in Fig. 7 does not include 40 the production of explosive mixtures by the admixture of air although this modification might be used in connection with a carburetor. The apparatus is designed to operate under pressure and the products which 45 have been heat treated while in the vapor state are to be passed out of the structure and through suitable separators or condensers such as are well known in the art. An annular casing 53 surrounds the side walls 50 54 of the vaporizing chamber 11 and is spaced therefrom and provides an annular heating chamber 55. A lining of refractory material 56 is provided within the casing 53 and around the annular chamber 55. Openings 57 in the side walls of the casing are 55 provided for the insertion of gas jet nozzles 58 leading from a supply pipe 59. These nozzles project into the annular chamber 55 tangentially. By this means a circumferential ring of flame may be applied to the exterior of the vaporizing chamber wall 54. A vent for the gases of combustion generated 60 by the flame from the nozzle 58 in the annular chamber 55 is indicated at 60. The lower 65 end of the shaft is tapered and is adapted

to project into oil which rises part way up into the oil inlet pipe 61. Centrifugal force will cause oil to be drawn up the tapered end of the shaft and discharged onto the upper surface of the cone. The inlet pipe 61 70 may have suitable control valves or float control means, not shown, to prevent oil from overflowing at the upper end. The material discharged from the cone is thrown off in the form of a vapor or fog and is 75 projected to the heat from the side walls 54. After this heat treatment the material is passed out of the vaporizing chamber through the discharge port 62 and through suitable separators or condensers such as 80 are well known in the art.

The various parts of the apparatus shown and described throughout the specification and claims and illustrated in the accompanying drawings may be made in any convenient manner and of any suitable material. The structure may be made of stamped sheet metal or cast according to the most advantageous method which can be used by the manufacturer. Changes in material and 85 size of the various parts of the structure may be made without departing from the scope 90 of the invention.

What I claim is:

1. In a carburetor, a casing having a vaporizing chamber, a vaporizer member within said chamber rotatably mounted to turn on a given axis and having a vaporizing surface, inclined at an angle to said axis, means for supplying liquid to be vaporized to said surface, means for rotating said surface at a predetermined speed according to the density of liquid employed and to cause the liquid to entirely vaporize from said surface in the form of a fine mist or fog, a mixing chamber for mixing air and vaporous fuel in ported communication with said vaporizing chamber to receive vapors therefrom, and means to control the admission of air into said mixing chamber. 95

2. In a carburetor, a casing having a vaporizing chamber, a vaporizer member within said chamber rotatably mounted to turn on a given axis and having a vaporizing surface inclined at an angle to said axis, means for supplying liquid to be vaporized to said surface, means for regulating the amount of liquid supplied to said surface, means for rotating said surface at a predetermined speed according to the density of liquid employed and to cause the liquid to entirely vaporize from said surface in the form of a fine mist or fog, a mixing chamber for mixing air and vaporous fuel in ported communication with said vaporizing chamber to receive vapors therefrom, and means to control the admission of air into said mixing chamber. 100

3. In a carburetor, a vaporizing chamber, rotary means in said chamber for produc- 105

ing a vapor, a mixing chamber communicating with said vaporizing chamber to receive vapors therefrom, an air passage communicating with said mixing chamber, and 5 means to regulate the admission of air to said mixing chamber including a valve positioned between said air passage and said mixing chamber.

4. In a carburetor, a vaporizing chamber, 10 rotary vaporizing means in said chamber for producing a constant supply of vapor, power means for actuating said rotary vaporizer means through the axis thereof, a mixing chamber communicating with said vaporizing chamber to receive vapors therefrom, an air passage communicating with said mixing chamber, and control means including a valve to regulate the admission of air from said air passage to said mixing chamber.

20 5. In a carburetor, a vaporizing chamber, rotary means in said chamber for producing a vapor, means in the path of such vapor for converting said vapor to a gas, a mixing chamber communicating with said vaporizing chamber to receive aeriform fuel therefrom and mix the same with air, an air passage communicating with said mixing chamber, and means to regulate the admission of air to said mixing chamber including a valve positioned between said air passage and said mixing chamber.

30 6. In a carburetor, a vaporizing chamber, rotary vaporizing means in said chamber for producing a constant supply of vapor, power means for actuating said rotary vaporizer means through the axis thereof, means in the path of such vapors for converting said vapor to a gas, a mixing chamber communicating with said vaporizing chamber to receive aeriform fuel therefrom and an air passage communicating with said mixing chamber, and control means to regulate the admission of air from said air passage to said mixing chamber.

40 7. In a carburetor, a casing having a vaporizing chamber, a vaporizer member within said chamber rotatably mounted to turn on a given axis and having a vaporizing surface disposed at an angle to the axis of rotation, means for supplying liquid heavier than gasoline to be vaporized to said surface, means for rotating said vaporizer member and surface at such speeds as to vaporize at least a portion of the liquid before it reaches said lateral edge of said vaporizing surface, a mixing chamber in parted communication with said vaporizing chamber to receive the vapors therefrom and mix the same with air, and valve means to control the admission of air into said mixing chamber.

50 8. In a carburetor, a casing having a vaporizing chamber, a vaporizer member within said chamber rotatably mounted to turn on a given axis and having a vaporizing sur-

face disposed at an angle to the axis of rotation, means for supplying liquid to be vaporized to said surface at a point adjacent the axis of rotation and on the side of said surface towards said axis, means for rotating said vaporizing member and surface at such a speed as to cause the liquid to entirely vaporize from said surface in the form of a fine mist or fog, a mixing chamber in ported communication with said vaporizing chamber to receive the vapors therefrom and mix the same with air, and valve means to control the admission of air into said mixing chamber.

60 9. A carburetor comprising a main casing having an air inlet passage, a fuel inlet passage, and a fuel mixing chamber for mixing air and vaporous fuel, a rotatable fuel vaporizing member within said casing, an adjustable air supply valve between said air inlet passage and said mixing chamber, control means to regulate the rotation of said vaporizer member, and means to regulate the position of said air supply valve.

70 10. A carburetor comprising a main casing having an air inlet passage, a fuel inlet passage for liquid fuel, and a mixing chamber for mixing air and vaporous fuel, a fuel vaporizer chamber within which fuel is vaporized communicating with said fuel inlet passage and with said mixing chamber, a rotatable fuel vaporizer member within said vaporizing chamber, means to regulate the application of liquid fuel to said vaporizer member, and means to regulate the flow of aeriform material through said mixing chamber.

80 11. A carburetor comprising a main casing having an air inlet passage, a fuel inlet passage for liquid fuel, and a mixing chamber for mixing air and vaporous fuel, a fuel vaporizing chamber within which fuel is vaporized communicating with said fuel inlet passage and with said mixing chamber, a rotatable liquid fuel vaporizer member within said vaporizing chamber, means to regulate the entrance of fuel from said fuel inlet passage to said fuel vaporizing chamber, and means to regulate the flow of aeriform material through said mixing chamber.

90 12. A carburetor comprising a main casing having an air inlet passage, a fuel inlet passage, and a mixing chamber for mixing air and vaporous fuel, a fuel vaporizing chamber communicating with said fuel inlet passage, a rotatable fuel vaporizer member within said vaporizing chamber, means to regulate the entrance of fuel from said fuel inlet passage to said fuel vaporizing chamber, and means to regulate the application of fuel to said vaporizer member.

100 13. A carburetor comprising a main casing having an air inlet passage, a fuel inlet passage, and a mixing chamber for mixing

- air and vaporous fuel, a fuel vaporizing chamber communicating with said fuel inlet passage and with said mixing chamber, a rotatable fuel vaporizer member within 5 said vaporizing chamber, an adjustable air supply means including a valve located between said air inlet passage and said mixing chamber, and means to regulate the application of fuel to said vaporizer member.
- 10 14. A carburetor comprising a main casting having an air inlet passage, a fuel inlet passage, and a mixing chamber for mixing air and vaporous fuel, a fuel vaporizing chamber communicating with said fuel inlet passage and with said mixing chamber, a rotatable fuel vaporizer member within 15 said vaporizing chamber, an adjustable air supply means including a valve located between said air inlet passage and said mixing chamber, and means to regulate the entrance of fuel from said fuel inlet passage 20 to said vaporizing chamber.
- 15 16. A carburetor comprising a main casting having an air inlet passage, a fuel inlet passage, and a mixing chamber for mixing air and vaporous fuel, a fuel vaporizing chamber communicating with said fuel inlet passage and with said mixing chamber, a rotatable fuel vaporizer within 25 said vaporizing chamber, an adjustable air supply means including a valve located between said air inlet passage and said mixing chamber, means to regulate the entrance of fuel from said fuel inlet passage to said fuel vaporizing chamber, and means to regulate the application of fuel to said vaporizer member.
- 30 17. A carburetor comprising a main casting having an air inlet passage, a fuel inlet passage, a mixing chamber for mixing air and vaporous fuel, and a vaporizing chamber communicating with said fuel inlet passage, a rotatable vaporizer member in said vaporizing chamber, an air valve between 35 said air inlet passage and said mixing chamber, and a fuel discharge conduit for vaporous fuel between said vaporizing chamber and said mixing chamber.
- 40 18. A carburetor comprising a main casting having an air inlet passage, a fuel inlet passage, a mixing chamber for mixing air and vaporous fuel, and a vaporizing chamber communicating with said fuel inlet passage, a rotatable vaporizer member in said vaporizing chamber, an air valve between 45 said air inlet passage and said mixing chamber, and a fuel discharge conduit for vaporous fuel entering said mixing chamber at a point in close proximity to said air valve.
- 55 19. A carburetor comprising a main casting having a circular vaporizing chamber, a fuel inlet passage communicating with said vaporizing chamber, an air inlet passage concentric with said vaporizing chamber, and a mixing chamber for mixing vaporous fuel and air, a rotatable vaporizer member within 60 said vaporizing chamber, and an air valve between said air inlet passage and said mixing chamber, the wall of said circular vaporizing chamber being provided with a plurality of fuel discharge ports arranged around the same and communicating with said mixing chamber.
- 65 20. A carburetor comprising a main casting having a circular vaporizing chamber, a fuel inlet passage communicating with said vaporizing chamber, an air inlet passage concentric with said vaporizing chamber, and a mixing chamber for mixing vaporous fuel and air concentric with said vaporizing chamber and said air inlet passage, a rotatable vaporizer member within 70 said vaporizing chamber, and an adjustable circular air valve between said air inlet passage and said mixing chamber and concentric with each.
- 75 21. A carburetor comprising a main casting having a circular vaporizing chamber, a fuel inlet passage communicating with said vaporizing chamber, an air inlet passage concentric with said vaporizing chamber, and a mixing chamber for mixing vaporous fuel and air concentric with said vaporizing chamber and said air inlet passage, a rotatable vaporizer member within 80 said vaporizing chamber, a primary adjustable air valve between said air inlet passage and said mixing chamber and concentric with each, a secondary adjustable air valve between said air inlet passage and said vaporizing chamber and concentric with each, and means for adjusting one of said valves to open in advance 85 of the other.
- 85 22. In a carburetor, a casing having a fuel vaporizing chamber, an intake pipe for liquid fuel communicating with the same, a rotatable vaporizer member within said vaporizing chamber comprising a vertical driven shaft, an inverted conical vaporizer having a circular periphery and mounted on the lower end of said shaft and having oblique walls extending upward toward said periph- 90

ery, and valve means carried by said vaporizer member for regulating the application of fuel to said vaporizer.

23. In a carburetor, a casing having a fuel vaporizing chamber, an intake pipe for liquid fuel communicating with the same, an air inlet passage, a mixing chamber for mixing air and vaporous fuel, a driven shaft, a high speed electric motor connected 10 to and in axial alignment with said shaft, and an inverted conical vaporizer mounted within said chamber on one end of said shaft and having a circular periphery with oblique walls extending from the shaft 15 toward said periphery.

24. In a carburetor, a casing having a fuel vaporizing chamber, an intake pipe for liquid fuel communicating with the same, rotatable vaporizer means comprising a driven 20 shaft, a high speed motor connected to and in axial alignment with said shaft, an inverted conical vaporizer mounted on one end of said shaft and within said chamber and having a circular periphery with oblique 25 walls extending from the shaft toward said periphery, and means carried by said vaporizer for conducting fuel to be vaporized from a point below said vaporizer to the upper surface of the same.

25. In a carburetor, a casing having a fuel vaporizing chamber within which fuel is vaporized, an intake pipe for liquid fuel connected to the same, rotatable vaporizer means within said chamber comprising a vertical 35 driven shaft, an inverted vaporizer cone of thin sheet metal within said chamber mounted on the lower end of said shaft and having a circular periphery with oblique walls extending from the shaft upward toward said 40 periphery, means for conducting fuel to be vaporized from a point below said vaporizer cone to the upper surface of the same, and manually controlled means for regulating the flow of fuel to the upper side of said 45 cone.

26. In a carburetor, a casing having a fuel vaporizing chamber, an intake pipe for liquid fuel communicating with the same, a rotatable vaporizer member within said vaporizing 50 chamber comprising a hollow driven shaft, an inverted vaporizer cone mounted on and encircling said shaft at the lower end thereof and having a circular periphery and oblique walls extending toward said 55 periphery, and means for regulating the application of liquid fuel to be vaporized to said cone comprising a valve rod extending through said hollow shaft and said cone and a valve at the lower end of said shaft operated by said valve rod.

27. In a carburetor, a casing having a fuel vaporizing chamber, an intake pipe for liquid fuel communicating with said chamber, an air inlet passage, and a mixing chamber

for mixing air and vaporous fuel, an air 65 valve between said air inlet passage and said mixing chamber, a rotatable fuel vaporizer member within said vaporizing chamber comprising a hollow driven shaft, an inverted vaporizer cone mounted on and encircling said shaft at the lower end thereof and having a circular periphery and oblique 70 walls extending upwardly toward said periphery, a fuel valve within said hollow shaft and the lower end thereof, and unitary means for actuating said air valve and said fuel valve.

28. In a carburetor, a casing having a fuel vaporizing chamber, an intake pipe for liquid fuel communicating with said chamber, 80 an air inlet passage, and a mixing chamber for mixing air and vaporous fuel, a primary air valve between said air inlet passage and said mixing chamber, a secondary air valve between said air inlet passage and said fuel 85 vaporizing chamber, a rotatable fuel vaporizer member within said vaporizing chamber comprising a hollow driven shaft, an inverted vaporizer cone mounted on and encircling said shaft and having a circular 90 periphery and oblique walls extending upwardly toward said periphery, a fuel valve within said hollow shaft and at the lower end thereof, and unitary means for actuating said primary and said secondary air 95 valves and said fuel valve.

29. In a carburetor, a casing having a fuel vaporizing chamber, an intake pipe for liquid fuel communicating with said chamber, an air inlet passage, and a mixing 100 chamber for mixing air and vaporous fuel, an air valve between said air inlet passage and said mixing chamber, a rotatable fuel vaporizer member within said vaporizing chamber comprising a hollow driven shaft, 105 an inverted vaporizer cone mounted on and encircling said shaft and having a circular periphery and oblique walls extending upwardly toward said periphery, a fuel valve within said hollow shaft and the lower end 110 thereof, a throttle valve in said mixing chamber, and unitary means for controlling said fuel valve, said air valve and said throttle valve.

30. In a carburetor, a casing having a fuel vaporizing chamber, an intake pipe for liquid fuel communicating with said chamber, an air inlet passage and a mixing chamber for mixing air and vaporous fuel, a primary air valve between said air inlet 115 passage and said mixing chamber, a secondary air valve between said air inlet 120 passage and said fuel vaporizing chamber, a rotatable fuel vaporizer member within said vaporizing chamber comprising a hollow driven shaft, an inverted vaporizer cone mounted on and encircling said shaft and having a circular periphery and oblique 125

walls extending upwardly toward said periphery, a fuel valve within said hollow shaft and at the lower end thereof, a throttle valve in said mixing chamber, and unitary means for actuating said primary and secondary air valves, said fuel valve and said throttle valve.

31. In a carburetor, a casing having a fuel vaporizing chamber, an intake pipe for liquid fuel communicating with the same, a rotatable vaporizer member within said vaporizing chamber comprising a driven shaft extending through said casing in one direction, a vaporizer cone having a circular periphery mounted on said shaft and having oblique walls extending from the latter toward said periphery, and a high speed electric motor connected to the end of said shaft projecting beyond said casing and in axial alignment with said shaft, and means for regulating the application of fuel to be vaporized to said cone.

32. In a carburetor, a casing having a central vaporizing chamber and an air intake passage concentric and in ported communication therewith, an adjustable air valve within said casing controlling communication between said air intake passage and said vaporizing chamber, a plunger connected to said valve and extending through said casing, and means movably mounted above said casing and adapted to be moved to actuate said plunger to operate said valve.

33. In a carburetor, a casing having a central vaporizing chamber and an air intake passage concentric therewith, an adjustable circular air valve within said casing and concentric with said air intake passage, a plurality of plungers spaced apart and connected to said valve and extending beyond said casing, and a plurality of operating members spaced apart in fixed relation to each other and adapted to be moved to actuate said plungers to operate said valve.

34. In a carburetor, a casing having a central vaporizing chamber and an air intake passage concentric therewith, an adjustable air valve within said casing between said air intake passage and said vaporizing chamber, a plunger connected to said valve and extending through said casing, a cam member movably mounted above said casing and adapted to be moved to actuate said plunger to operate said valve, and means to vary the pitch of said cam member.

35. In a carburetor, a casing having a central vaporizing chamber and an air intake passage concentric therewith, an adjustable circular air valve within said casing and concentric with said air intake passage, a plurality of plungers spaced apart and connected to said valve and extending beyond said casing, a plurality of

cam members spaced apart in fixed relation to each other and adapted to be moved to actuate said plungers to operate said valve, and means to vary the pitch of said cam members.

36. In a carburetor, a casing having a central vaporizing chamber and an air intake passage concentric therewith, a rotatable vaporizer member within said chamber, a fuel valve within said casing for regulating the passage of liquid fuel to said vaporizer member, a plunger connected to said fuel valve and projecting through said casing, and a cam member movably mounted above said casing and adapted to be moved to actuate said plunger for operating said fuel valve.

37. In a carburetor, a casing having a central vaporizing chamber and an air intake passage concentric therewith, a rotatable vaporizer member within said chamber, a fuel valve within said casing for regulating the passage of liquid fuel to said vaporizer member, a plunger connected to said fuel valve projecting through said casing, a cam member movably mounted above said casing and adapted to be moved to actuate said plunger for operating said fuel valve, and means to vary the pitch of said cam member.

38. In a carburetor, a casing having a central vaporizing chamber and an air intake passage concentric therewith, an adjustable air valve within said casing between said air intake passage and said vaporizing chamber, a plunger connected to said air valve and projecting through said casing, a rotatable vaporizer member within said chamber, a fuel valve within said casing for regulating the passage of fuel to said vaporizer member, a plunger connected to said fuel valve and projecting through said casing, a cam member movably mounted above said casing and adapted to be moved to actuate said plunger to operate said air valve, a second cam member mounted above said casing and adapted to actuate the plunger connected to said fuel valve, and unitary control means for operating said cam members.

39. In a carburetor, a casing having a central vaporizing chamber and an air intake passage concentric therewith, a circular adjustable air valve within said casing and concentric with said air intake passage, a plurality of plungers spaced apart and connected to said valve and projecting through said casing, a rotatable vaporizer member within said chamber, a fuel valve within said casing for regulating the passage of liquid fuel to said vaporizer member, a plunger connected to said fuel valve and projecting through said casing, a cam member movably mounted above said cas-

ing and adapted to be moved to actuate said plunger on said fuel valve, and a plurality of cam members spaced apart and adapted to be moved to actuate said plungers connected to said air valve to operate the latter.

40. In a carburetor, a casing having a central vaporizing chamber and an air intake passage concentric therewith, an adjustable air valve within said casing between said air intake passage and said vaporizing chamber, a plunger connected to said air valve and projecting through said casing, a rotatable vaporizing member within said chamber, a fuel valve within said casing for regulating the passage of fuel to said vaporizer member, a plunger connected to said liquid fuel valve and projecting through said casing, a cam member movably mounted above said casing and adapted to be moved to actuate said plunger to operate said air valve, a second cam member mounted above said casing and adapted to actuate the plunger connected to said fuel valve, and means to vary the pitch of said cam members.

41. In a carburetor, a casing having a central vaporizing chamber and an air intake passage concentric therewith, a circular adjustable air valve within said casing and concentric with said air intake passage, a plurality of plungers spaced apart and connected to said valve and projecting through said casing, a rotatable vaporizer member within said chamber, a fuel valve within said casing for regulating the passage of liquid fuel to said vaporizer member, a plunger connected to said fuel valve and projecting through said casing, a cam member movably mounted above said casing and adapted to be moved to actuate said plunger on said fuel valve, a plurality of cam members spaced apart and adapted to be moved to actuate said plungers connected to said air valve to operate the latter, and means to vary the pitch of said cam members.

42. In a carburetor, a casing having a central vaporizing chamber and an air intake passage concentric therewith, an adjustable air valve within said casing between said air intake passage and said vaporizing chamber, a plunger connected to said valve and extending through said casing, a cam member movably mounted above said casing and adapted to be moved to actuate said plunger to operate said valve, and means to vary the pitch of said cam member comprising a secondary cam member adapted to be moved with respect to said first cam member to vary the inclination of the surface of the latter.

43. In a carburetor, a casing having a central vaporizing chamber and an air intake passage concentric therewith, an adjustable cir-

cular air valve within said casing and concentric with said air intake passage, a plurality of plungers spaced apart and connected to said valve and extending beyond said casing, a plurality of cam members spaced apart in fixed relation to each other and adapted to be moved to actuate said plungers to operate said valve, and means to vary the pitch of said cam members comprising a member movably mounted with respect to said cam members and carrying secondary cam members spaced apart in fixed relation and adapted to engage said first cam members.

44. In a carburetor, a casing having a central vaporizing chamber and an air intake passage concentric therewith, an adjustable circular air valve within said casing and concentric with said air intake passage, a plurality of plungers spaced apart and connected to said valve and extending beyond said casing, a pivotally mounted support on said casing, and a plurality of cam members on said support spaced apart in fixed relation to each other and adapted to be moved to actuate said plungers to operate said valve, movement of said support member acting to actuate said plungers by engagement with said cams. 80 85 90 95

45. In a carburetor, a casing having a central vaporizing chamber and an air intake passage concentric therewith, an adjustable circular air valve within said casing and concentric with said air intake passage, a plurality of plungers spaced apart and connected to said valve and extending beyond said casing, a pivotally mounted support on said casing, a plurality of cam members on said support spaced apart in fixed relation to each other and adapted to engage said plungers, and a circular member slidably mounted with respect to said support member and carrying secondary cam members adapted to engage said first cam members to vary the inclination of the surfaces of the latter. 95 100 105

46. In a carburetor comprising a main 110
casing having a central vaporizing chamber,
an air inlet passage, a mixing chamber for
mixing air and aeriform fuel, and a fuel in-
let passage for liquid fuel communicating
with said vaporizing chamber, a rotatable 115
fuel vaporizer member within said vaporiz-
ing chamber and adapted to discharge and
vaporize fuel, and a fuel heating medium
for heating aeriform fuel within said casing
encircling said vaporizer member and locat- 120
ed around said vaporizer member.

47. In a carburetor comprising a main casing having a central vaporizing chamber, an air inlet passage, a mixing chamber for mixing air with aeriform fuel, and a fuel inlet passage for liquid fuel communicating with said vaporizing chamber, a rotatable fuel vaporizer member within said vaporiz- 125

- ing chamber and adapted to discharge and vaporize fuel, and a heating medium within said vaporizing chamber encircling said vaporizer member for heating aeriform fuel.
- 5 48. In a carburetor comprising a main casing having a central vaporizing chamber, an air inlet passage, a mixing chamber for mixing air and aeriform fuel, and a fuel inlet passage for liquid fuel communicating with said vaporizing chamber, a rotatable fuel vaporizer member within said vaporizing chamber comprising an inverted vaporizer cone of thin sheet metal having a circular periphery and mounted on said shaft 10 and having oblique walls extending toward said periphery, said cone being adapted to discharge vaporized fuel, and an electrically heated member within said chamber spaced from and encircling said cone and adapted 15 to heat the vaporized fuel discharged from the latter.
49. In a carburetor comprising a main casing having a central vaporizing chamber, an air inlet passage, a mixing chamber for 20 mixing air and aeriform fuel, and a fuel inlet passage for liquid fuel communicating with said vaporizing chamber, a rotatable fuel vaporizer member within said vaporizing chamber comprising an inverted vaporizer 25 cone of thin sheet metal having a circular periphery and mounted on said shaft and having oblique walls extending toward said periphery, said cone being adapted to discharge vaporized fuel, and a circular electrically heated member within said chamber spaced from and encircling spirally said 30 cone and adapted to heat the vaporized fuel discharged from said cone.
50. A carburetor comprising a main casing having a central vaporizing chamber, an air inlet passage, a mixing chamber for 35 mixing air and aeriform fuel, and a fuel inlet passage for liquid fuel communicating with said vaporizing chamber, a rotatable fuel vaporizing member within said vaporizing 40 chamber and adapted to discharge and vaporize fuel, an intermediate heating chamber between said vaporizing chamber and said mixing chamber, a heating medium within said intermediate heating chamber, and communicating passages between said vaporizing chamber and said intermediate chamber and between said intermediate chamber and said mixing chamber.
- 55 51. A carburetor comprising a main casing having a central vaporizing chamber, an air inlet passage, a mixing chamber for mixing air and aeriform fuel, and a fuel inlet passage for liquid fuel communicating with 45 said vaporizing chamber, a rotatable fuel vaporizer member within said vaporizing chamber adapted to discharge and vaporize fuel, a series of communicating ports between said vaporizing chamber and said mix-

ing chamber, a protective gauze screen covering said ports, and an air valve between said air inlet passage and said mixing chamber located in proximity to said gauze screen.

52. A carburetor comprising a main casing having a central vaporizing chamber, an air inlet passage, a mixing chamber for mixing air and aeriform fuel, and a fuel inlet passage for liquid fuel communicating with said vaporizing chamber, a rotatable fuel vaporizer member within said vaporizing chamber adapted to discharge and vaporize fuel, a fuel heating member heated electrically within said vaporizing chamber and encircling said vaporizer member and adapted to heat the vaporized fuel discharged from the same, a primary air valve between said air inlet passage and said mixing chamber, and a secondary air valve encircling said vaporizing chamber and on the opposite side of said heating member from the periphery of said vaporizer member and constituting a valve controlled opening between said air intake passage and said vaporizing chamber.

53. In a carburetor, a casing having a vaporizing chamber, a rotatable vaporizer cone within said chamber adapted to be rotated at high speed and to centrifugally discharge fuel in the form of vapor, a heating element located within said chamber opposite to said cone and adapted to receive the vapor discharged from the cone and to chemically change the same, and means for mixing said changed vapors with air to form a combustible mixture.

54. In an apparatus for vaporizing liquids, a casing having a vaporizing chamber, a vaporizer member within said chamber rotatably mounted to turn on a given axis and having a vaporizing surface, inclined at an angle to said axis, means for supplying liquid to be vaporized to said surface, means for regulating the amount of liquid supplied to said surface, and means for rotating said surface at a predetermined speed according to the density of the liquid employed and to cause the liquid to entirely vaporize from said surface in the form of a fine mist or fog, a mixing chamber connected to said vaporizing chamber to receive vapors therefrom, and means to control the admission of air into said mixing chamber.

55. In an apparatus for vaporizing liquids, a casing having a vaporizing chamber, a vaporizer member within said chamber rotatably mounted to turn on a given axis and having a vaporizing surface inclined at an angle to said axis, means for supplying liquids to be vaporized to said surface, means for rotating said surface at a predetermined speed according to the density of the liquid employed and to cause the liquid to entirely vaporize from said surface in the form of

a fine mist or fog, a mixing chamber connected to said vaporizing chamber to receive vapors therefrom, and means to control the admission of air into said mixing chamber.

5 56. A carburetor for using hydrocarbon liquids of relatively high boiling points, comprising an outer casing having therein a vaporizing chamber, a vaporizer member having an interior conically shaped vaporizing surface rotatably mounted within said chamber to turn on the axis of a cone, means to supply said liquid to said interior conical surface in proper quantity to provide a film on the surface, means for rotating said vaporizing member at proper speeds which combined with the angle of said vaporizing surface causes combined pressure and friction of said liquid film on said surface to vaporize said liquid from said surface within the limits thereof in the form of a fine mist or fog, a mixing chamber in ported communication with said vaporizing chamber, an air passage leading thereto, and an

air valve governing the admission of air to said mixing chamber.

25 57. A carburetor for using liquids which are vaporized with difficulty, comprising an outer casing containing an enclosing chamber, a surface of limited extent within said chamber mounted to rotate about an axis 30 and inclined at a proper angle thereto, means for supplying liquid to said surface on the side toward the axis, means for rotating the surface at such high speed as, at the angle of said surface, to cause combined pressure 35 and friction of the liquid upon the surface to vaporize said liquid from said surface within the limits thereof in the form of a fine mist or fog, a mixing chamber in ported communication with said enclosing chamber, an air passage leading to said mixing chamber, and an air valve governing the admission of air to said mixing chamber.

40 In testimony whereof I have hereunto set my hand.

ARTHUR H. EDDY.
